UNITED STATES PATENT OFFICE.

BENJAMIN GROSS AND ROBERT A. GOELLER, OF NEW YORK, N. Y., ASSIGNEES TO GENERAL ELECTRIC COMPANY, A CORPORATION OF NEW YORK.

MULTIUNIT PANEL.

Application filed February 23, 1921. Serial No. 447,230.

To all whom it may concern:

Be it known that we, BENJAMIN GROSS, a citizen of the United States, and a resident of New York, county of Bronx, and 5 State of New York, and ROBERT A. GOELLER, a citizen of the United States, and a resident of New York, county of Bronx, and State of New York, have invented certain new and useful Improvements in Multiunit 10 Panels, of which the following is a specification.

This invention relates to electric control panels and has for its object the provision of a panel of such character that it may be 15 built up to any desired capacity by the additions of stock parts, the arrangement and construction being such that all the desired features of high grade "made-to-order" panels are incorporated into the apparatus. The invention makes possible 20 quantity production of high grade electric control panels and enables the capacity of the panel to be readily increased as needs may require by adding parts without interfering with the apparatus already installed 25 or interrupting service.

The invention is carried into effect by providing a master base to or on which is secured one or more common unit bases. 30 These unit bases support switch mechanisms which are connected to bus-bars arranged on the base or bases. The bus-bars are arranged between the common unit bases and bases of the switch mechanism, an arrangement that permits the switch bases to be 35 readily removed or installed or other switch units to be added to the panel without interfering with the already installed mechanism.

Other objects and features of novelty of 40 the invention will be pointed out in the detailed description thereof and others will become apparent as the description proceeds.

Referring now to the drawings forming part of this specification—

45 Fig. 1 is an elevation of one embodiment of the invention, the panel for convenience of illustration being shown with its lower edge at the right hand side of the sheet.

Fig. 2 is a section on the planes of the 50 irregular line A—B—C—D on Fig. 1.

Fig. 3 is a section on the plane of line 3—3 on Fig. 2, parts being omitted.

Fig. 4 is a view similar to the lower part 55 of Fig. 2 but showing a different form of switch.

Fig. 5 is a disassembly plan with some of the parts shown in section.

In the drawings like characters of reference designate like parts throughout the several views.

The apparatus forming the subject of the present invention is shown as mounted within in a suitable cabinet 10 of such dimensions as to allow wiring space around the apparatus, the cabinet being provided with a cover 65 C and having suitable doors 10^a and 10^b through which access may be had to the enclosed apparatus, this arrangement being more or less conventional.

Supported within the cabinet 10 is a base 70 11 on which the panel mechanisms are mounted or supported. This base is preferably made of metal so as to provide a rigid support and for convenience of description is termed the master base. Arranged at the 75 four corners of the base are angle iron brackets 12 having turned under extensions 12^a at one side by which they are secured to the master base, the extensions serving also as means to space the master base from 80 the back of the cabinet to provide an air space therebetween. Means permitting the master base to be detachably secured to the cabinet are provided at the corners and conveniently consists of plates 13 bifurcated 85 at one end to enable them to straddle screw bolts 14 or the like projecting from the back of the cabinet. Overlying and secured to these plates are foot-like extensions 12^b of the corner irons 12.

90 Adapted for suitable securement on the master base 11 are sub or common unit bases 15 which are substantial duplicates so that they may be interchanged. These unit bases are adapted to support individual bases 16 95 which carry suitable control elements or switches. In the drawings the subbases 15 are shown as supporting a pair of switch bases 16 disposed in opposite relation thereon. In order to provide for ready and accurate mounting of the switch bases 16 on the subbases 15, the subbase 15 is stepped as at 17 to provide a shoulder against which a shoulder near one end of the switch base 16 may abut. The base 16 may be centered 100 on the subbase by any suitable means as by a pillar 18 (Fig. 4) rising from the subbase 15 and entering a socket in the other base 16. Screws 19 secure the base 16 to the subbase, while the latter is secured to 110

the master base 11 by screws 20. The bases 15 and 16 are preferably of molded material and molded into the bases are suitable screw sockets and screw studs to enable proper securing of the various parts.

Supported on the switch bases 16 are switches 5 of any suitable or preferred type, the drawings showing the rotary type in Fig. 4 and the toggle or tumbler type in the other figures, the apparatus as a whole, however, being quite independent of the type of switch used. Mounted on the subbases 15 are in the present assembly three bus-bars 25 the middle one being the neutral. This showing however, is merely illustrative and is therefore not to be taken as a limitation of the invention. As shown in the drawings the panel is of the double branch type, two switch units being mounted on a common subbase. It will be readily apparent however that the panel may be either of the single branch or double branch type without departing from the spirit of the invention. The switches are shown as of the double pole type since this is the form commonly employed.

The bus bars 25 are arranged in spaced relation on the subbase. The switch bases 16 are undercut to receive the bus bars and the undercuts are wide enough to enable bus bars of different sizes or capacity to be used with switch bases or units of a given size. Electrically connected to the underlying bus-bar is a contact 27 having a bent-up wing 28 with which a switch blade is adapted to be electrically connected as will be readily understood. The contact is stepped and suitably secured to the switch base, the rise of the contact from the bus-bar being through a slot or opening in the base. The connection between the bus-bar and contact is preferably effected through the instrumentality of a screw stud molded into and projecting from the subbase 15, the stud passing through the bus-bar. A nut 38 on the stud terminal completes the connection.

Opposite the contacts 27 at the other end of the switch base is a contact 31 having a wing 30 similar to the wing 28 and for a similar purpose as will be readily understood. Extending from the contact is a fuse-terminal clip 32.

Mounted on the subbases in spaced relation to the contacts 31 on the switch bases 16 are contacts 33 having wings 34 similar to the wings 32 for receiving the fuse-terminal. These contacts 33 are provided with means 35 for securing circuit wires. The contacts 31 and 33 are arranged above the switch base proper near the door of the cabinet so as to render the fuses 5 more accessible than has heretofore been the case in other panels and are supported on step-like elevations which rise from the bases 15 and 16 respectively. The channel between these eleva-

tions enables the fuses to be manipulated without any danger of bruising the fingers as so often happens in manipulating fuses in ordinary panels. The fuse arrangement just described is an important feature of the invention.

The subbase 15 adjacent the contact 33 is provided with a barrier flange 36 which is slotted opposite the means 35, the slots in the flange serving to confine the circuit wires in definite position with respect to the securing means 35 and to each other. Another advantage of providing a slotted barrier flange is that barrier linings, hereinafter more fully referred to, may be seated on the top of the flange without any thought being taken of the wires as has heretofore been necessary when the barrier lining itself was slotted.

Connection between the neutral middle bus-bar and switch is made by contacts 27' having wings 28', the contacts being supported on the switch base 16 in spaced relation to the contacts 27 and provided with rabbeted terminals whereby when a pair of switch bases 16 is supported on the subbases 15, the adjacent terminals of the contacts 27' may be electrically connected to the middle bus-bar by common securing means.

The construction thus far described provides a panel which may be built up as future needs may require without interfering with the switch units already installed. Inasmuch as the bus-bars lie in contact with the subbases 15 and are of a length sufficient to accommodate future expansion of the panel it is only necessary in providing an additional switch unit to properly align the switch base on the subbase, this alignment being easily effected by means of the centering pillar 18 which enters into an opening in the switch base. The base 16 is then secured to the subbase 15 by means of the screws 18 and 19. Electrical connections with the bus-bars and the contacts 27 and 27' are then readily effected in the manner already pointed out.

The cabinet 10 and master metal base 11 are made preferably of a size to take care of future expansion of the panel. The subbases 15 are suitably secured to the master base 11 and extend throughout the width of the master base 11. In the drawings the master base 11 is shown as supporting a plurality of subbases 15 which are of a width equal to that of the switch bases but if desired the subbase may be made wide enough to support a plurality of adjacent switch bases. The switch bases 16 may also be made of a size to take care of a plurality of switches. In short, the sub and switch bases may be made in any convenient size and are preferably of molded material.

The terminals of the bus bars 25 are sup-

ported on insulated plates 60 which are suitably supported on the master base 11 at opposite ends thereof. Insulating barriers 61 extend from the plates 60 and provide protective barriers for the bus bar terminals. It will be observed that the barriers are spaced on either side of the bus-bars, a sufficient distance to take care of bus-bars having a greater width than those shown.

In order to close off the electrical parts from all sides, barrier linings are provided at the sides of the panel. These barriers preferably take the form of insulating liner plates 40 which are detachably secured to the angle irons 12 which extend from the corners of the master base 11. Any convenient means 41 for securing the linings to the angle irons may be provided. These barriers 40 extend into close proximity to the cover C of the cabinet and effectually protect the mechanisms of the panel against mechanical injury and also serve as fire barriers.

In order to further close off the electrical parts of the apparatus below the switch operating means, a cover plate B having barrier walls 45 is provided opposite the switch mechanism. This cover plate is provided with openings through which the switch handles 51 project. The manner of supporting the cover plate will vary with the type of switch employed. When the switch includes a bracket 50 secured to the switch bases 16 the cover may be supported by said brackets. The cover plate is preferably built up from sections "b" each of which is as wide as the switch base over which it is mounted and of desired length, thus enabling the safety barrier to be built up as switch units are added to the panel. The meeting edges of the plates "b" are preferably stepped to overlap as shown at "c" in Fig. 3 to prevent open spaces due to variations in manufacture. The outside marginal edges of the plates "b" are preferably flanged as at 46 to enable the side and end walls 45 of the barriers to be readily mounted thereon. The construction above described provides a safety cover which may be built up as the panel is built up and is an important feature of the invention.

In some types of switches as in the rotary type shown in Fig. 4, the safety cover may be supported between the button handle and casing of the switch, the button being removable from its stem to permit the cover to be slipped thereover, the cover shown being a molded structure B'.

It will be understood that the cabinet is closed by the plate or cover C after the panel has been inserted within the cabinet and that access may be had to the panel through doors 10^a and 10^b. The spaces between the panel proper and the ends of the

cabinet 10 serve as wire receiving compartments, the wires being entered through the slots in the barrier flanges 36 and connected to the securing means 35.

While we have shown the middle or neutral bus-bar as arranged between the adjacent ends of the switch bases and parallel to the other two bus-bars, the neutral bus-bar may be arranged transversely to said bus-bars at one end of the panel without departing from the spirit of the invention. Such an arrangement is preferable when switches of the single pole type are used. With such a construction, one of the fuses for each circuit is placed near the adjacent main bus-bar, and the other near the transverse neutral bus-bar. This arrangement permits the switches to be arranged in closer relation since they are all of the same polarity. It will also be understood that a main control switch and fuses may be in circuit with the bus bars at any convenient point as at one side of the panel. Other arrangements and features of construction will readily occur to those skilled in the art and we therefore intend no limitations except as may be imposed by the appended claims.

While the invention has been described with considerable particularity it is to be distinctly understood that the invention is not limited to any particular details, it being the intention to set forth the scope of the invention in the appended claims.

Having thus described the invention, what we claim as new and desire to secure by Letters Patent is:

1. In an electric control panel, the combination of a subbase, a bus-bar supported thereon, a switch base detachably mounted on the base over the bus-bar, said bases having interfitting parts for preventing relative movement between them, spaced steps rising from each of the bases at adjacent ends, and fuse-supporting means on the steps.

2. In an electric control panel, the combination of a subbase, a bus-bar supported thereon, a switch base detachably mounted on the base over the bus-bar, said subbase being constructed to form an abutment against which the switch base engages, and spaced fuse supports on the bases in a plane which is spaced from the plane of the switch base.

3. In an electric control panel, the combination of a subbase, a bus-bar mounted thereon, a switch base detachably mounted on the subbase over the bus-bar, said subbase being constructed to form an abutment against which the switch base engages, fuse-supporting means on said bases, and a slotted barrier flange rising from the subbase adjacent the fuse-supporting means thereon.

4. In an electric control panel, the combination of a subbase, a bus-bar mounted on the subbase, a switch base detachably

mounted on the subbase over the bus-bar, steps extending from adjacent ends of the bases and defining a channel between them, fuse-supporting means on said steps and a 5 slotted barrier flange rising from the step on the subbase adjacent the fuse-supporting means thereon.

5. In an electric control panel, the combination of a subbase having a pair of steps 10 at one end, a bus-bar supported on said base, a switch base detachably secured to said base with one of its ends in engagement with the rise of the lowest step, the other end overlying the bus-bar, and fuse clips on the second 15 step of the base and on the adjacent end of the switch base.

6. In an electric control panel, the combination of a subbase having a pair of steps 20 at one end, a bus-bar supported on said base, a switch base detachably secured to said base with one of its ends in engagement with the rise of the lowest step, the other end overlying the bus-bar, fuse clips on the second step of the base and on the adjacent end of 25 the switch base, wire securing means connected to the clip on the subbase, and a barrier flange extending from the second step, said flange having openings therein through which conducting wires are adapted 30 to pass for connection to said securing means.

7. In combination, a master base, angle irons secured to the corners thereof, a subbase supported on said master base and having a slotted barrier flange rising from one 35 end thereof, a barrier lining secured to opposite angle irons and overlying said barrier flange, a bus-bar supported on the subbase, a switch base supported on the subbase and overlying the bus-bar, and a post terminal 40 on the subbase adjacent said slotted barrier flange and in line with a slot therein.

8. In combination, a master base, angle irons secured to the corners thereof, a subbase 45 supported on said master base and having a slotted barrier flange rising from one end thereof, a barrier lining secured to opposite angle irons and overlying said flange, a bus-bar supported on the subbase, a switch 50 base supported on the subbase and overlying the bus-bar, a post terminal on the subbase adjacent said slotted barrier flange and in line with a slot therein, and a switch base mounted on said subbase and having fuse-supporting means opposite the post terminal. 55

9. In combination, a master base, a plurality of common subbases mounted side by side in definite positions on the master base and adapted to be interchanged thereon, a 60 bus-bar extending transversely of the subbases, a switch base adapted for securement to any one of the common subbases and overlying the bus-bar, each of said subbases being constructed to form a shoulder 65 at a distance from one of its ends against

which a part of the switch base is adapted to abut, and fuse-terminal supporting means at the adjacent ends of the subbase and the switch base in a plane above the top of the switch base. 70

10. In an electric control panel, the combination of subbase having abutments near each end, a plurality of bus-bars on the subbase between said abutments, a pair of oppositely disposed switch bases in engagement with the respective abutments on the subbase, the adjacent ends of the switch bases overlying different bus-bars, an opening in each switch base through which contact may be made with the underlying bus-bar, and fuse-terminal supporting means at the other ends of said switch bases and near the ends of the subbase. 75 80

11. In an electric control panel, the combination of a subbase, a bus-bar, a switch base mounted on said subbase and overlying the bus-bar, said subbase being constructed to form a shoulder against which the switch base abuts, a step on the switch base at that end which abuts against said shoulder, fuse-supporting means mounted on the last named step, and fuse-supporting means mounted on the subbase at a point spaced from the fuse supporting means on the switch base and on the same plane therewith. 90 95

12. In an electric control panel, the combination with a master base, of a subbase having a channel with stepped sides, a plurality of bus-bars supported on the base in the channel, and a pair of oppositely disposed switch bases in abutting relation with the lower steps of the channel, each switch base overlying one bus-bar. 100

13. In an electric control panel, the combination with a master base, of a subbase having a channel with stepped sides, a plurality of bus-bars supported on the base in the channel, a pair of oppositely disposed switch bases in abutting relation with the lower steps of the channel, each switch base overlying one bus-bar, each said switch bases having an opening to expose the underlying bus-bar, and electrical connections mounted on the switch bases to permit electrical contact to be made with the underlying bus-bar. 110 115

14. In an electric control panel, the combination with a master base, of a subbase having a channel with stepped sides, a plurality of bus-bars supported on the base in the channel, a pair of oppositely disposed switch bases in abutting relation with the lower steps of the channel, each switch base overlying one bus-bar, fuse-and-wire-securing means mounted on the uppermost steps of the subbase, and fuse-and-switch contacts mounted on the switch bases in spaced relation to said means. 120 125

15. In an electric control panel, the combination with a master base, of a subbase 130

having a channel with stepped sides, a plurality of bus-bars supported on the base in the channel, a pair of oppositely disposed switch bases in abutting relation with the lower steps of the channel, each switch base overlying one bus-bar, fuse-and-wire-securing means mounted on the uppermost steps of the subbase, a step on the switch bases opposite the uppermost step on the subbase 10 and on a level therewith, said steps defining a channel between them, and fuse contacts mounted on the switch base steps.

16. In an electric control panel, the combination with a master base, of a subbase 15 having steps rising from one end thereof, a switch base supported on the subbase and having a step at one end thereof on a level with the uppermost step on the subbase and defining therewith a channel, and contact-making means on the steps on either side of said channel.

17. In an electric control panel, the combination with a master base, of a subbase having steps rising from one end thereof, 25 a switch base supported on the subbase and having a step at one end thereof on a level with the uppermost step on the subbase defining therewith a channel, contact-making means on the steps on either side of said channel, and a bus-bar between said bases.

18. In an electric control panel, the combination of a sub-base having a raised step at one end thereof, a switch base having a raised step at one end thereof and positioned on the sub-base to bring said steps opposite but spaced from each other, fuse 35

contacts on said steps and a fuse connecting said contacts.

19. In an electric control panel, the combination of a sub-base having a raised step at one end thereof, a switch base having a raised step at one end thereof and positioned on the sub-base to bring said steps opposite but spaced from each other, fuse 40 contacts on said steps, a fuse connecting said contacts, and a cover over said panel having therein a door over said fuse.

20. In an electric control panel, the combination of a sub-base having a raised step 45 at one end thereof, a plurality of switch bases each having a raised step at one end thereof and positioned on the sub-base to bring their steps opposite but spaced from the sub-base step, fuse contacts on said steps, fuses connecting said contacts, and a cover plate over the switch bases terminating near the inner ends of the fuses.

21. In an electric control panel, the combination of a sub-base having a raised step 50 at one end thereof, a plurality of switch bases each having a raised step at one end thereof and positioned on the sub-base to bring their steps opposite but spaced from the sub-base step, fuse contacts on said steps, fuses connecting said contacts, a cover plate over the switch bases terminating near the inner ends of the fuses, and a cover over said panel having therein a door over said fuses. 55

In witness whereof, we have hereunto set our hands this 21st day of February, 1921.

BENJAMIN GROSS.
ROBERT A. GOELLER.
